UNITED STATES PATENT OFFICE.

WILLIAM WALLACE WEEKS, OF BROOKLYN, NEW YORK, ASSIGNOR TO ELEVATOR SUPPLIES COMPANY, INC., A CORPORATION OF NEW JERSEY.

COMBINED ELEVATOR-DOOR CLOSURE AND SWITCH.

Application filed October 22, 1923. Serial No. 670,074.

To all whom it may concern:

Be it known that I, WILLIAM WALLACE WEEKS, a citizen of the United States, residing at 366 Fourth Street, Brooklyn, N. Y., have invented a certain new and useful Improvement in Combined Elevator-Door Closures and Switches, of which the following is a clear, full, and exact description.

The present invention relates particularly to a door closure and an electric switch combined therewith, by means of which elevator doors and similar devices may be operated, and by which the elevator door may be checked in either its opening or closing movement or both, and which will serve at the same time to control the elevator operating circuit so as to open and close the circuit with the opening and closing movement of the door.

Broadly, the invention comprises an electric switch combined with an elevator door operating means, whether of the pneumatically operated form having cushioning means, or of the form embodying only a door check cushioning with either a liquid or a gas.

In the use of elevator door closures in which the elevator door is operated by hand and also in the use of the more recent automatic elevator door operating devices, it has been customary to employ a separate switch for opening and closing the elevator door operating circuit when the elevator door is opened and closed. The upkeep of such switches has been extremely high and has necessitated a great deal of care and attention in the replacement of worn parts so as to maintain efficient elevator operation. Furthermore, it has been the custom for elevator operators to disconnect the switches from the toggle levers so that the circuit will not be opened when the elevator doors are opened, thereby attaining more rapid elevator operation by starting the elevator before the elevator doors are closed and allowing the doors to close after the elevator has left the particular floor. This practice has considerably increased the danger in elevator operation, which it is the purpose of the switch to overcome by opening the elevator operating circuit when the elevator doors are opened.

The present invention provides a switch serving the same purpose as that formerly

employed, but which is not accessible and which may not be tampered with or disconnected except by two persons, and the task of disconnecting the switch is sufficient to discourage attempts to disconnect it so that it will fail to open the circuit when the elevator doors are opened.

The primary object of the present invention is to provide an elevator door operating mechanism and switch, combined in one apparatus, in which the switch is not accessible to be tampered with or to be shifted. By this means the operation of the elevator circuit switch will be made dependent entirely upon the operation of the elevator door.

Another object of the invention is to provide a combined switch and door closer which may be manufactured at a low cost and in which a high efficiency is attained in the making and breaking of the elevator operating circuit.

Another object of the invention is to provide a switch, which may be operated in the presence of oil, by which excessive heating due to arcing in the switch during the making and breaking of the circuit is prevented, thus decreasing the wear and depreciation of the switch.

With these and other objects in view, the invention comprises the various features hereinafter described and more particularly defined in the claims.

The invention will be described in connection with the accompanying drawings showing a preferred embodiment thereof, in which—

Fig. 1 is a vertical sectional view of a combined elevator door check and switch, comprising the preferred form of my invention;

Fig. 2 is a detail sectional view of the circuit closing means in the device shown in Fig. 1;

Fig. 3 is a cross sectional view taken on the line 3—3 of Fig. 1;

Fig. 4 is a cross sectional view taken on the line 4—4 of Fig. 1;

Fig. 5 is a view in elevation partly in section, of the combined elevator door check and switch in mounted position, showing the manner in which it may be attached to toggle levers or other mechanism to be operated, and

Fig. 6 is a view illustrating the mode in

which the combined check and switch may be mounted in connection with elevator doors, the device being shown operatively connected to the ordinary form of toggle levers.

In the operation of elevator doors it is common practice to open and close the doors by means of toggle levers of some form to which checking means or dampening means are connected in order to prevent slamming or jarring in the movements of the door. One form of checking device which has been developed embodies closing means comprising a spring which is compressed when the door is opened and which assists in the closing movement of the elevator door by means of the energy attained in the opening movement thereof. It is to this form of elevator door operator that the present invention is particularly applied, as illustrated in the drawings, although the invention is not limited to the embodiment in a device of the form shown, and I contemplate embodying a switch in a similar way in other forms of closures, such as in the pneumatically-operated elevator door operating mechanisms.

Referring more particularly to the accompanying drawings, 2 represents a cylinder casing to which a plunger cylinder 4 is attached by any suitable means, such as a connecting member 6, having a flanged portion 10 which is connected to the cylinder casing 2 by screwthreaded connections 8. The connecting member 6, which is preferably made integral with the plunger cylinder 4, serves in combination with the plunger cylinder and its head as a closure for one end of the casing 2. Within the casing 2 is a spring retaining member 12 which is attached to a plunger rod 14, which has connected thereto at its lower end a plunger 16 operating in the plunger cylinder 4. At the lower end of the cylinder 4 is a cylinder head or cap 18, which is preferably formed with a lug 20, which may be connected to a suitable bracket 23 serving as an attaching means for one end of the device, when in operative position. The device is further supported in position by means of a connection 15 between the plunger rod 14 and the toggle levers 17 attached to an elevator door or doors to be operated, as illustrated in Figure 6.

The upper portion of the cylinder 2 is closed by means of a cylinder head or cap 22 through which the plunger rod 14 passes. The cap or head 22 and the piston or retaining means 12 serve to hold a compression spring 24 in position within the casing 2, by means of which the toggle levers are operated to return the elevator door to its closed position after it has been manually opened. In the operation of the plunger 16 in the cylinder 4 to cushion the movements

of the toggle levers and door, I preferably employ oil, by means of which the movements of the plunger in the cylinder may be controlled. Within the walls of the cylinder 4 I provide an oil passage 25 extending from the lower end of the cylinder to the upper or middle portion thereof. The means for regulating or varying the amount of cushioning action in the device comprises a regulating screw 21 in the oil passage, which may be adjusted in position from without so as to attain any desired amount of cushioning or checking action.

In order to provide a switch within the device whose operation will be dependent upon the movements of the elevator door, I employ two circuit terminals 26, 28, which pass through the base of the connecting member 6 into the interior of the cylinder 2. The leads 30, 32 of the controller circuit of an elevator may be attached to the terminals 26, 28 exterior to the cylinder by any suitable means such as nuts 34, 36. It is preferable to enclose the exterior portions of the terminals in a box, which may be locked or otherwise secured, as will be apparent to those skilled in the art, so as to prevent disconnecting the wires 30, 32 or tampering with the connections, but for the sake of simplicity such locking means have not been shown in the drawings. The terminals 26, 28 are made of any suitable conducting material, and must be insulated from the cylinder casing to prevent short circuiting therethrough. In order to insulate the terminals, insulating members 38, 40, are provided by means of which all metallic contact between the terminals and portions of the cylinder is avoided. The upper portions of the terminals 26, 28, are preferably laterally extended or flattened into heads 42, 44 by means of which a large surface of contact may be attained between the terminals and a conducting member 46 by means of which the circuit through the terminals is opened and closed. The conducting member 46 comprises an annular ring of suitable conducting material, such as copper, for example, and is so disposed in the device that when the elevator door is opened by a small amount ($\frac{1}{2}$ " or thereabouts), the elevator operating circuit will be opened, thereby preventing movement of the elevator until the elevator door is again closed or substantially closed.

In order that the elevator circuit may not be opened with movements of less than a certain predetermined amount, as $\frac{1}{2}$ " for example, and also to provide a pressure contact between the conducting member 46 and the terminals 26, 28 when the switch is closed, the conducting member 46 is connected to an insulating member 48 (see Fig. 2) by yieldable means, such as two set screws 50, 52 which are rigidly connected to the

member 46 and are arranged to slide in openings in the member 48 with limited movement. The insulating member 48 is preferably an annular ring of bakelite or other suitable non-conducting material. The set screws 50, 52 which pass through openings 51, 53 (see Fig. 4) in the annular ring 48 have heads 55, 57, (see Figs. 1 and 2) which cooperate with projections in the openings 10 which serve to support the set screws 50, 52, and to limit their movement relative to the insulating member 46. The conducting member, together with the screws 50, 52, is normally forced downwardly by means of 15 compression springs 54, 56, positioned around the set screws in recesses 59, 61 in the member 48. By this means the annular conducting member 46 is held against the terminals 26, 28 when the elevator door is in closed position. The annular non-conducting or insulating member 48 is suitably attached to the spring retaining means 12 as by set screws 11, 13, for example. The spring retainer 12 is attached to the plunger rod 14 in any suitable manner as by means 20 of a pin and slot connection 58, whereby when the plunger rod 14 is operated through the movements of the toggle lever 17, the spring-retaining means 12 is moved correspondingly together with the non-conductor 25 48. The conducting member 46 remains in contact with terminals 26, 28 until in the upward movement of the plunger rod and the member 48, the projections in the openings 51, 53 come into contact with the heads 55, 57 of the set screws 50, 52, thus raising the conducting member 46 out of contact with the terminals 26, 28, and breaking the elevator operating circuit. It is apparent 30 that the set screws 50, 52, may be made of any desired length so as to obtain a breaking of the circuit at any predetermined position of the member 48 corresponding to a certain predetermined position of the elevator door.

In the operation of the device the plunger cylinder contains a sufficient amount of oil to suitably cushion the movements of the plunger, and the lower portion of the cylinder 2 preferably contains oil to a height above the terminals 26, 28 and the conducting member 46 when in closed position, so that when the circuit is opened the oil will prevent arcing and will serve also to maintain the switch contact members cool, and thus prevent deterioration thereof.

While the switch has been described as operating in oil, which constitutes the preferred form of my invention, I desire to have it understood that the switch would operate in air, as will be apparent to those skilled in the art, and instead of a door closer using a spring to assist in the return movement of the elevator door, I may employ merely a dash-pot to attain cushioning

action, combined with a controller circuit switch embodied therein in the manner as set forth in connection with the door check and closer as above described. It is to be understood, furthermore, that various 70 changes and modifications may be made in the device without departing from the spirit or scope of the invention as defined in the following claims.

Having thus described the invention, what 75 is claimed as new is:

1. In a device of the class described, a door check, means for operatively connecting said check to a door, dampening means in said check, and an electric switch within 80 said door check for opening and closing a circuit with the movements of said door.

2. In a device of the class described, a door check, means for operatively connecting said check to a door, means in the said 85 check for cushioning the movements of said door, circuit terminals within the said check and a conducting member operatively connected to said dampening means for opening and closing a circuit between said terminals with the opening and closing movements of said door.

3. In a device of the class described, a door check, means for operatively connecting said check to an elevator door, cushioning means in said check adapted to cushion the movement of said elevator door, an electric switch within said check having stationary terminals and a movable conducting member operatively connected to said dampening means, whereby a circuit through the said terminals will be opened and closed with the opening and closing movements of said elevator door.

4. In a device of the class described, an 105 elevator door check, dampening means in said check and an electric switch within said door check for closing the elevator operating circuit when the elevator door to which said check is connected is closed.

5. In a device of the class described, a door check, means for operatively connecting said check to an elevator door, dampening means in said check, an electric switch 110 immersed in oil within said check, said switch being operatively connected to said elevator door, whereby the switch will be opened when the elevator door is moved from its closed position.

6. In an elevator door closer, a check 120 adapted to be operatively connected to the toggle levers of an elevator door, a casing, a plunger cylinder connected to said casing, a plunger in said plunger cylinder, spring means in said casing for returning said elevator door to its closed position after opening movement thereof, and an electric switch in said casing comprising switch terminals and a movable contact member, said contact member being adapted to operate 125 130

with the movements of said elevator door to open and close a circuit through said switch.

7. In a door check, a casing, cushioning means in the casing comprising a plunger and plunger cylinder, a passageway in the walls of said plunger cylinder, means for regulating the passage of oil through said passageway from one portion of said cylinder to another, whereby the movements of said plunger may be cushioned or checked during predetermined portions of the stroke of said plunger, an electric switch in said casing adapted to be connected to an elevator controller circuit, means for opening and closing the circuit through said switch, comprising a conducting member operatively connected to said plunger, and means whereby the circuit through said switch will be opened after a predetermined limited movement of said plunger.
8. In a device of the class described, a casing, a piston in said casing, means for connecting one of said parts to a mechanism to be operated, a plunger cylinder connected to said casing, a plunger in said plunger cylinder, a plunger rod connected to said plunger and said piston, spring means in said casing for returning said plunger and piston after movement thereof whereby said mechanism is operated, an electric switch within said casing comprising switch terminals and a conducting member adapted to be moved in and out of contact with said terminals, whereby a circuit through said terminals may be opened and closed, and means for operatively connecting said conducting member to said piston whereby the opening and closing movements of the said switch are made dependent upon the movement of said mechanism.
9. In a device of the class described, a door check, dampening means in said check, an electric switch within said check comprising switch terminals and a movable conducting member, means for operatively con-

necting said movable conducting member to said dampening means, whereby a limited movement of said dampening means may take place without opening the circuit through said switch.

10. In a device of the class described, a door check, means for operatively connecting said check to the toggle levers of an elevator door, cushioning means in said check comprising a plunger operating in a plunger cylinder, means for maintaining oil in said cylinder to cushion the movements of said plunger and said mechanism, switch terminals in said casing adapted to be operatively connected to the controller circuit of an elevator, a conducting member adapted to open and close a circuit through said terminals, means for yieldably supporting said conducting member, said means comprising an insulating member, and spring means for holding said conducting member in pressure contact with said terminals, when said elevator door is in closed position.

11. In a device of the class described, a door check, means for operatively connecting said check to the toggle levers of an elevator door, cushioning means in said check comprising a plunger operating in a plunger cylinder, means for maintaining oil in said cylinder to cushion the movements of said plunger and said mechanism, switch terminals in said casing adapted to be operatively connected to the controller circuit of an elevator, a conducting member adapted to open and close a circuit through said terminal, means for yieldably supporting said conducting member on said piston, said means comprising an insulating member, and spring means for holding said conducting member in pressure contact with said terminals when said elevator door is in closed position.

Signed at New York city, N. Y., this 19th day of October, 1923.

WILLIAM WALLACE WEEKS.
